CLAIM

(22) Filed: **Jun. 28, 1999**

The ornamental design for an appliance suitable for self-diagnosis for measuring the bodily states of a human being, as shown and described.

(30) **Foreign Application Priority Data**

DESCRIPTION

Dec. 29, 1998 (DE) 4 98 12 599

FIG. 1 is a perspective front elevational view of an appliance suitable for self-diagnosis for measuring the bodily states of a human being from above, showing my design;

(51) **LOC (7) Cl.** **10-04**

FIG. 2 is a front view of the appliance;

(52) **U.S. Cl.** **D10/87; D10/92**

FIG. 3 is a side view thereof;

(58) **Field of Search** D10/87, 92; 600/547;

FIG. 4 is a side view thereof;

177/180, 188, 238, 239, 240, DIG. 10,

FIG. 5 is a rear view thereof;

210 R

FIG. 6 is a top plan view thereof;

(56) **References Cited**

FIG. 7 is a bottom plan view thereof;
